CHRISTMAS TREE ORNAMENT OR SIMILAR ARTICLE

Alfred A. Flaster, New York, N. Y.

Application March 31, 1958, Serial No. 50,233

Term of patent 7 years

(Cl. D29—1)

Fig. 1 is a front elevational view of a Christmas tree ornament, showing my new design;

Fig. 2 is an edge view; and

Fig. 3 is an edge view thereof rotated rearwardly 90 degrees from the position shown in Fig. 2.

Both sides of all parts of the snowflake have the same ornamentation on the front and back.

The stippling indicates spangles.

I claim:

The ornamental design for a Christmas tree ornament or similar article, substantially as shown and described.
